UNITED STATES PATENT OFFICE.

VALENTINE GEORGE CRITTALL, OF BRAINTREE, ENGLAND, ASSIGNOR TO THE CRITTALL MANUFACTURING COMPANY, LIMITED, OF BRAINTREE, ENGLAND.

WINDOW AND CASEMENT.

1,132,834.

Specification of Letters Patent. Patented Mar. 23, 1915.

Application filed June 11, 1914. Serial No. 844,568.

To all whom it may concern:

Be it known that I, VALENTINE GEORGE CRITTALL, a subject of the King of Great Britain, residing at Braintree, in the county 5 of Essex, England, have invented new and useful Improvements in Windows and Casements, of which the following is a specification.

This invention relates to windows and 10 casements having metal frames which slide up and down in metal jambs. The body of the jamb consists of a flat metal plate which is preferably the head of a T the stem of which is let into the wall. Along the outer 15 edge of the plate there is a flange projecting at right angles from it. This flange may be conveniently formed of an angle iron riveted to the plate. A strip of bronze or the like is preferably fixed to the inner face of 20 the flange. Near the middle of the plate is fixed a grooved bar, on the inner side of which is preferably fixed a strip of bronze or the like. A second grooved bar is fixed at the inner edge of the plate. Each sliding 25 frame consists of a double flanged or trough shaped bar and the outer faces of the outer flanges of these bars preferably have fixed to them strips of bronze or the like. The strip on the outer flange of the upper frame 30 slides in contact with the strip on the inner face of the flange of the jamb plate, while the inner flange of the upper frame runs in the groove of the central grooved bar. The strip on the outer flange of the lower frame 35 slides in contact with the strip on the inner side of the central grooved bar, while the inner flange of the lower frame runs in the groove of the inner grooved bar. Each frame is provided with rollers (preferably 40 four) which are pivoted between their flanges and bear against the outer faces of the two grooved bars.

The invention is applicable to the casements described in the specification No. 45 1,002,228, the outer frames of such casements being made to slide up and down in the jambs as above described. The drawings show such an arrangement.

Figure 1 is an outside front elevation and 50 Fig. 2 is a vertical section on the line 2—2, Fig. 1; Fig. 3 is two local horizontal sections, the front part being on the line 3—3, Fig. 1, and the rear part on the line 3—3, Fig. 1. Figs. 4, 5 and 6 show details.

55 *a a* are vertical T irons let into the side

walls *b*. One of these walls is shown in Fig. 3 but for the sake of clearness they are omitted in Figs. 1 and 2.

a¹ a¹ are angle irons secured to the T irons by rivets *a²*.

a³ a³ are strips of bronze fixed to the angle irons *a¹*.

c c are the outer bars of the upper sash of casements constructed according to the former specification, and *d d* are the bars 65 of the inner frame pivoted at *e e* to the bars *c*. Only vertical bars *c* are employed, there being no corresponding bars at the top and bottom.

c¹ c¹ are bronze strips fixed to the bars *c* 70 and sliding in contact with the strips *a³*.

f f are rollers mounted on studs *f¹* fixed to plates *f²* which are secured to the webs of the bars *c* by rivets *f³* as shown at Figs. 3 and 6.

g g are angle irons on which the rollers *f* run. These angle irons have slots *g¹* (Figs. 4 and 5) in them and they are secured by clamping strips *h* and screws *h¹* which screw into holes in the T irons *a*. This construction allows of accurate adjustment in the fixing of the angle irons *g* so that when the casement is erected the strips *c¹* can be firmly but not too tightly pressed against the strips *a³*.

h² are bronze strips fixed to the clamping strips *h*.

The lower sash is adjustably secured in place in an exactly similar manner.

j j are the outer vertical bars and *k k* are 90 the bars of the inner frame pivoted at *l l* to them.

j¹ j¹ are bronze strips fixed to the bars *j*. They are in contact with the strips *h²* and their rollers *m* run upon angle irons *n* which 95 are exactly similar to the angle irons *g* and are as before adjustably secured in place by clamping strips *o* and screws *o¹*.

The upper and lower sashes balance one another the tops of the bars *c* and *j* being 100 connected together by chains (not shown) which pass over pulleys *p*.

q q are plates fixed to the lower bar *d* and upper bar *k* to make a tight joint between the upper and lower sashes.

r is a cast iron sill situated between the lower ends of the T irons *a* and secured to them by bolts (not shown).

r¹ is a drain hole to allow condensation to escape.

What I claim is:—

The combination of a jamb, an outer flange fixed to the jamb, an angle piece forming an inner flange and having slots in it, a clamping strip, screws passing through the slots and securing the clamping strip to the jamb whereby said angle piece is made adjustable, a vertical sash bar the

outer face of which is in direct contact at all times with the outer flange, and rollers piv- 10 oted to the sash bar and in direct contact with the inner flange.

VALENTINE GEORGE CRITTALL.
